UNITED STATES PATENT OFFICE.

CARL BAUER, OF CHICAGO, ILLINOIS, ASSIGNOR TO DOETSCH & BAUER COMPANY, OF CHICAGO, ILLINOIS, A CORPORATION OF ILLINOIS.

DESIGN FOR A SETTEE FRAME OR SIMILAR ARTICLE.

Application filed October 8, 1928. Serial No. 28,393. Term of patent 3½ years.

To all whom it may concern:

Be it known that I, CARL BAUER, a citizen of the United States, residing at Chicago, in the county of Cook and State of Illinois, have invented a new, original, and ornamental Design for a Settee Frame or Similar Article, of which the following is a specification, reference being had to the accompanying drawing, forming a part thereof.

The figure represents a settee frame or similar article, showing my new design. The ornamentation shown is continued around the lower end portion of the frame.

I claim:

The ornamental design for a settee frame or similar article as shown and described.

In witness whereof, I hereunto subscribe my name this 1st day of October, 1928.

CARL BAUER.
